UNITED STATES PATENT OFFICE.

ANTONIO N. TRULLENCH, OF LUCENA, PHILIPPINE ISLANDS.

TOOL.

1,375,984.

Specification of Letters Patent. Patented Apr. 26, 1921.

Application filed October 29, 1919. Serial No. 334,154.

To all whom it may concern:

Be it known that I, ANTONIO N. TRULLENCH, a citizen of the United States, residing at Lucena, Tayabas, in Philippine Islands, have invented certain new and useful Improvements in Tools, of which the following is a specification.

My invention relates to new and useful improvements in a tool, and more particularly to a combination tool particularly adapted for use of electrical or wire workers.

The principal object of the invention is the construction of a tool of this character which is simple and inexpensive in construction and of compact form so that it may be easily carried upon the person or in a tool box.

Another object of the invention is the provision of a tool adapted for stretching and cutting wires used in electrical or other work.

A further object is the provision of means for locking the tool in adjusted position when used as a wire stretcher.

With these and other objects in view my invention consists of the novel details of construction and arrangement of parts which will be more clearly understood from the following specification and drawings in which:—

Figure 1 is a side elevation,

Fig. 2 is a bottom plan,

Fig. 3 is a transverse vertical section on the line 3—3 of Fig. 1, and

Fig. 4 is a detailed sectional view on the line 4—4 of Fig. 2 looking in the direction of the arrow.

In carrying out my invention the tool has the general outline of a pair of pliers. The handles are indicated at 1 and 2 and are pivotally connected at 3. The handle 1 is beveled at one end to form a screw-driver 4 and the opposite end forms a jaw 5. An integral knife 6 is formed on the top of the jaw 5 as indicated in Figs. 1 and 3. A concave serrated recess 7 is formed in the underface of the jaw 5, intermediate the ends, and the under side of the jaw is also serrated as indicated at 8. Semi-circular recesses 9 are formed on each side of the jaw, intermediate the pivot point 3 and recess 7, and a knife 10 is formed integral with the jaw and within the recesses. A pointed projection 11 is formed on the end

of the jaw for the purpose to be later described.

The handle 2 is provided on the top surface with a recess 12 and a projection 13. A gimlet 14 is pivotally connected to the handle at 15 and when raised is adapted to engage the projection 13 as illustrated in Fig. 1. When lowered the gimlet is adapted to be received in the recess 12. The top of the handle 2 is substantially straight as indicated in Fig. 1. Notches 16 are formed in the handle 2, adjacent the pivot point 3, and when the handles 1 and 2 are in their normal position these notches are adapted to register with similar notches formed in the handle 1 which are not shown in the drawings. The handle 2 is formed on one end with a jaw 17 of the same configuration as the jaw 5, and is provided with the concaved serrated recess 18 adapted to register with the recess 7 in the jaw 5. This jaw 17 is also provided with the serrations 19 adapted to coöperate with the serration 8 of the jaw 5. The jaw 17 is further provided on each side with the semi-circular recesses 20, similar to the recesses 9, and a knife 21 is formed integral with the jaw, within the recesses, and adapted to coöperate with the knife 10, and as is illustrated in Fig. 3 the sharpened edges of the knives 9 and 21 are adapted to meet when the jaws are closed. A pointed projection 22 is formed on the end of the jaw 17 and coöperates with the pointed projection 11 to make up a circular pointed projection. 90

A pocket or socket 23 is formed on the under surface of the jaw 17 and a perforated projection 24 is formed on the under face of the jaw 17 adjacent the open end of the pocket or socket 23. An arcuate-shaped ratchet bar 25 is adapted to pass through the perforation in the projection 24 as illustrated in Figs. 2 and 4, and this ratchet bar is provided on each end with a plate 26. A slideable pawl 27 is received in the socket 100 or pocket 23 and is adapted to engage the teeth of the ratchet bar 25. A coiled spring 28 is received in the socket or pocket 23 behind the pawl, and normally holds the forward end of the pawl in engagement with the ratchet bar. An elongated opening 29 is formed in the under face of the socket 23, and a projection 30 on the pawl 27 extends through said elongated opening 105 and provides a finger-hold for operating 110

the pawl. As illustrated in Figs. 1 and 2 when the parts are in assembled position the pointed ends of the projections 11 and 22 will lie intermediate the plates 26 and on 5 a plane therewith.

From the above detailed description it is thought that the construction and operation of the device will be clearly understood. I have provided a combination tool which is 10 particularly adapted for the use of wire workers and provides means whereby the wire may be cut, scraped, and stretched in position. I also provide means, in the form of a gimlet, for boring holes for receiving 15 screws or the like and also provide a screw-driver for inserting the screws. For cutting small wires I have provided knives 10 and 21, and for cutting larger wires I have provided the recesses or notches 16 in the 20 handle 2 and similar notches in the handle 1. The knife 6 may be used for scraping insulated wire so as to form proper connection. If it is desired to grip the wire for stretching or other purposes the wire may 25 be inserted in the serrated recesses 7 and 18 or gripped between the serrated faces 8 and 19 of the jaws. When the wire is to be stretched it is gripped as described and the pointed ends of the projections 11 and 22 30 may be engaged with the object to which the wire is to be attached. The plates 26 on the arcuate-shaped ratchet bar 25 may also be engaged against the object. By drawing upon the handles the wire will be stretched 35 and the pawl 27 will pass over the teeth in the ratchet bar 25 and hold the handles in position for holding the wire stretched until it may be attached in position. The pawl 40 may be released by grasping upon the projection 30 and forcing the pawl backward against the tension of the coiled spring 28. The perforated projection 24 forms a guide 45 for the ratchet bar.

The foregoing description and the drawings have reference to what may be considered the preferred or approved form of my invention. It is to be understood that I 50 may make such changes in construction and arrangement and combination of parts, materials, dimensions, etc., as may prove expedient and fall within the scope of the appended claims.

Having thus fully described my invention what I claim as new and desire to secure by 55 Letters Patent is:—

1. A tool comprising pivotally connected handles, a jaw formed on each handle, a perforated projection formed on one jaw, a

ratchet bar passing through said perforated projection, and means carried on the jaw 60 for engaging the ratchet bar.

2. A tool comprising a pair of pivotally connected handles, a jaw formed on each handle, a perforated projection formed on one jaw, an arcuate-shaped ratchet bar passing through the perforated projection, and a 65 slidable pawl carried by the jaw and adapted to engage the ratchet bar.

3. A tool comprising a pair of pivotally connected handles, a jaw formed on one end 70 of each handle, a perforated projection formed on one jaw, an arcuate-shaped ratchet bar slidably mounted in the projection, a pocket formed on the jaw adjacent the perforated projection, a pawl slidably mounted in the pocket, and a spring carried 75 in the pocket and engaging the pawl for normally holding it in engagement with the ratchet bar.

4. A tool comprising a pair of pivotally connected handles, a jaw formed on each handle, a pointed projection formed on the end of each jaw, a perforated projection formed on one jaw, an arcuate-shaped ratchet bar slidably through the perforated 85 projection, a pocket formed on this jaw, and a spring-controlled pawl slidably mounted in the pocket for engagement with the ratchet bar.

5. A tool comprising pivotally connected 90 handles, a jaw formed on the end of each handle, a ratchet bar slidably connected to one jaw so as to extend at right angles to the path of movement of the jaws, and means for engaging the ratchet bar for the purpose specified.

6. A tool comprising pivotally connected handles, jaws formed on the handles, a ratchet bar slidably connected to the tool, means on the tool for engaging the ratchet bar, and means on the ends of the ratchet bar for engaging against an object for the purpose and in the manner specified.

7. A tool comprising pivotally connected handles, jaws formed on the handles, a ratchet bar slidably connected to the tool, means on the tool for engaging the ratchet bar, and plates on the ends of the ratchet bar for engaging against an object for the purpose and in the manner specified.

In testimony whereof I affix my signature in presence of two witnesses.

ANTONIO N. TRULLENCH.
